BY HIS ATTORNEY.

James J. Williamson

UNITED STATES PATENT OFFICE.

EDWARD L. EGERMAYER, OF GRAND FORKS, NORTH DAKOTA.

DRUM.

Application filed December 13, 1924. Serial No. 755,660.

This invention relates to musical drums and especially to means for yieldingly tensioning the heads thereof, being applicable to snare, bass, or tympani drums and banjos, as well as tom-toms or other musical instruments employing a percussive head.

It is an object of the invention to provide in a drum, a simple but highly efficient device for tensioning the percussive heads and automatically maintaining the proper tension thereof, despite variations in the temperature or atmospheric pressure.

It is a further object in such a device to provide means for readily adjusting the tension of the heads comprising few parts and capable of being assembled or disassembled quickly.

An additional object of the invention is to provide a resilient tensioning device for drums which will permit the drum heads to give slightly, when under unusual strain, thereby minimizing the danger of fracture of the skin or vellum.

More specifically, it is an object of the invention to provide a resilient collar adapted to bear against the skin hoop or head ring of the drum and compressed by an outer compression ring impelled toward the drum head.

30 A still further object of the invention is to provide adjustable resilient tightening means for impelling the compression ring towards the drum head.

These and other objects of the invention 35 will be apparent from the following description made in connection with the accompanying drawings, wheréin like characters refer to similar parts throughout the several views, and wherein—

40 Fig. 1 is a view mostly in side elevation and partly in section of the preferred form of the invention with some parts broken away;

Fig. 2 is a vertical section taken on the 45 line 2—2 of Fig. 1;

Fig. 3 is a detail view of one of the rod receiving sockets detached;

Fig. 4 is a plan view, on a diminished scale, of the resilient collar employed in the 50 improved drum;

Fig. 5 is a cross section of the same taken on the line 5—5 of Fig. 4; and

Fig. 6 is a fragmentary vertical section of a modified form of the invention.

Referring to the preferred form of the invention by characters of reference, the usual cylindrical body or shell is indicated by the numeral 7 across the ends of which are stretched the percussive heads 8, usually constructed of skin or vellum, and secured to the usual skin hoops 9 which fit over the ends of the body 7. Compression rings 10, preferably of annular angle bar construction, are disposed on the outer side of each of the heads 8 in axial alignment therewith and in spaced relation thereto. Between the compression rings 10 and the skin hoops 9, resilient collars 11 are disposed, best shown in Figs. 4 and 5, having struck up therefrom or otherwise secured thereon a plurality of 70 leaf springs 11^a adapted to project angularly outward and be contacted by the inner side of compression rings 10.

The compression rings 10 have a plurality of circumferentially spaced, preferably circular apertures therethrough, each provided with seats 10^a in the outer surfaces of said rings. A plurality of spring baskets or tubular members 12, having flanged heads, are adapted to project through compression 80 rings 10 and have their flanged ends disposed in seats 11. The bottoms of the spring baskets 12 project inwardly and are perforated to permit the tightening rods 13 to be passed therethrough with the enlarged tightening heads 14 disposed within 85 the baskets. Coiled springs 15 are interposed between the heads 14 and the bottoms of the baskets 12. The tightening rods 13 project inwardly and terminate in threaded 90 engaging ends 13^a. A plurality of upstanding posts 16 are bolted or otherwise secured in circumferentially spaced relation to the outer side of the body of shell 7, preferably at the cross sectional center thereof. Each 95 of the posts 16 is provided with an outer substantially rectangular securing head 16^a, preferably extending longitudinally with the axis of the drum. Anchoring members 17, having threaded receiving sockets 17^a, 100 are provided, with flanges 17^b having substantially rectangular apertures therethrough extending at right angles to their axes. The apertures are obviously adapted to fit over the heads 16^a, permitting the 105 anchoring members 17 to be pivotally secured to the post 16. The threaded sockets 17^a engage the threaded ends 13^a of the

tightening rods, and, of course, permit tension to be placed on the coiled springs 15 and consequently on the compression rings 10 and imparted through the resilient collars 11 to the skin hoops 9. Two sets of resilient elements are, therefore, employed to tension the drum heads 8.

It is, of course, obvious that the tension on the drum heads 8 may be increased or decreased by the manipulation of the slotted heads 14 on the tightening rods disposed within the baskets 12. The tension of the heads may thus be regulated by means of a screw driver or simple tool adapted to engage the slotted heads 14.

It will be seen that, although considerable tension be put upon the drum heads, there will always be a high degree of resiliency present in the tensioning devices, which will afford sufficient elastic give to prevent the heads from becoming fractured, when the drum is beaten unusually hard, or when temperature or atmospheric conditions tend to tighten the heads.

It will also be seen that this same resiliency afforded by the spring collar and the plurality of coiled springs will tend, at all times, to equalize the actual tension on the heads 8. The tonal quality of the drum will, therefore, be substantially constant and it will, therefore, not be necessary to tune the drum each time it is used or to loosen the heads when the drummer has finished playing.

The resilient collar 11, provided with the plurality of leaf springs 12, affords a novel and efficient means for uniformly applying the desired resilient tension to the skin hoops 9, while the spring-equipped tightening rods resiliently impel the compression rings 10 towards the drum heads.

In the modified form of the invention, illustrated in Fig. 6, the coiled springs are dispensed with and the resiliency is entirely furnished by the spring collars. In Fig. 6, the body of the drum is indicated by the numeral 20, having a drum head 21 secured to head ring 22. The resilient collar 23, as in the preferred form of the invention, is interposed between the skin hoop 22 and the compression ring 24. The baskets or tubular members 25 are seated and pass through the compression rings 24, as in the preferred form, and the tension rods 26 are threadedly engaged in the same manner, as has been previously described. The heads 27 of the tightening rods 26, however, engage the bottom of the basket 25 and pull directly thereupon, without the intervention of the coiled spring. This modified form may be more cheaply manufactured and has also been found to give satisfactory results.

From the above description, it will be seen that a highly efficient resiliently ten-

sioned drum has been invented capable of ready adjustment and involving few parts. The novel features of the device have been carefully tested and found to be highly successful for the purposes intended.

It will, of course, be understood that various changes may be made in the form, details and arrangement of the parts without departing from the scope of the invention. It will likewise be understood that the invention is equally applicable to banjos or other musical instruments employing a stretched vellum head.

What is claimed is:—

1. A drum or analogous instrument comprising a body having an open end, a head stretched over said end, a skin hoop for said head encircling said body and movable longitudinally thereof, resilient means contacting the outer side of said skin hoop, and compression means held against said resilient means to yielding tension said head. 80

2. A drum or analogous instrument comprising a body having an open end, a head stretched over said end, a skin hoop for said head encircling said body and movable longitudinally thereof, a resilient collar axially aligned with and contacting the outer side of said skin hoop, and a compression ring held against said resilient means to yielding tension said head. 90

3. The structure set forth in claim 2, and said resilient collar comprising an annular member carrying a plurality of outwardly projecting leaf springs. 100

4. A drum or analogous instrument comprising a body having an open end, a head stretched over said end, a skin hoop for said head encircling said body and movable longitudinally thereof, a resilient collar contacting the outer side of said skin hoop, and compression means contacting the outer side of said resilient collar, and means for securing said compression means to the body of said drum adjustable longitudinally of said body. 105

5. A drum or analogous instrument comprising a body having an open end, a head stretched over said end, a skin hoop for said head encircling said body and movable longitudinally thereof, a resilient collar contacting the outer side of said skin hoop, a compression means contacting the outer side of said resilient collar, resilient means 115 securing said compression ring to said body and adjustable longitudinally of said body. 120

6. A drum or analogous instrument comprising a body having an open end, a head stretched over said end, a skin hoop for said head encircling said body and movable longitudinally thereof, a compression ring on the outer side of said skin hoop adapted to tension said head, a plurality of baskets carried by said compression ring, inwardly 125

disposed thereof, with their outer edges substantially flush with the outer surface of said compression ring, and means extending into said baskets for adjustably securing said compression ring to said body to vary the tension of said head.

7. The structure set forth in claim 6, and

said means comprising headed tightening rods and coiled springs disposed between the heads of said rods and the bottoms of said baskets.

In testimony whereof I affix my signature.

EDWARD L. EGERMAYER.
